ATTORNEYS

UNITED STATES PATENT OFFICE.

OLIN HENRY WILSON, OF CEDAR VALE, KANSAS.

CUT-OUT.

Application filed September 6, 1924. Serial No. 736,360.

all whom it may concern:

Be it known that I, OLIN H. WILSON, a citizen of the United States, and a resident of Cedar Vale, in the county of Chautau-

qua and State of Kansas, have invented cer-
tain new and useful Improvements in Cut-
Outs, of which the following is a specifica-
tion.

This invention relates to exhaust release
10 devices especially adapted for use on inter-
nal combustion engines.

Briefly stated an important object of this
invention is to provide an exhaust release
device, having simple means whereby the
15 same may be opened to permit of the free
and unobstructed movement of the exhaust
gases to the atmosphere without the neces-
sity of first traveling through the muffler
20 and without the necessity of making objec-
tionable bends.

A further object of the invention is to
provide simple means whereby the im-
proved cut out device may be incorporated
25 in an exhaust line either during the manu-
facture or assembly of an automobile or at
any time thereafter without inconvenience
or the exercise of unusual skill.

A further object is to provide a cut out
30 device which is of highly simplified con-
struction, durable in use and cheap to man-
ufacture.

Other objects and advantages will be ap-
parent during the course of the following
description.

35 In the accompanying drawing forming a
part of this application and in which like
numerals are employed to designate like
parts throughout the same:

Figure 1 is a perspective of the im-
40 proved cut-out device applied;

Figure 2 is a vertical transverse sectional
view through the improved cut out device
applied;

Figure 3 is a vertical transverse sectional
45 view taken on the line 3—3 of Figure 2;

Figure 4 is a detail view, partly in sec-
tion, of the movable disk section of the cut-
out device, and

Figure 5 is a side elevation of a slightly
50 modified form of invention.

In the drawing wherein for the purpose
of illustration is shown a preferred embodi-
ment of the invention, the numeral 5 design-

nates an exhaust pipe which extends from
an internal combustion engine and serves to
conduct products of combustion to the muf-
fler 6.

The exhaust line is divided to permit of
the installation of the cut out device 8 and
to distinguish the rear portion 9 of the ex-
haust pipe from the forward portion of the
exhaust pipe the said rear portion of the
pipe may be designated the muffler pipe.

In carrying out the invention I provide
co-acting disk-shaped sections 11 and 12
65 having their opposed sides flatly in abut-
ment and provided with lugs or ears 13 and
14, respectively, for the reception of a bolt
16 by means of which the disks or plates
are hingedly connected.

The exhaust line 5 and consequently the
section 11 which is rigidly secured thereto
are relatively stationary since the exhaust
line is supported by a bracket 18 secured to
any stationary part of the vehicle, such as
75 the frame by means of a fastening device
20. The co-acting sections 11 and 12 are
formed with openings 22 and 23 adapted
for registration so as to establish communi-
cation between the exhaust pipe 5 and the
muffler pipe 9. It will be seen that the ex-
haust conducting members 5 and 9 extend
80 through bosses 25 and 26 and are rigidly
secured thereto by set screws 27 and 28 or
other suitable fastening devices.

85 The disk-shaped member 12 which is the
main movable member of the structure is
limited in its movement in one direction by
means of an arcuate stop and guide flange
30 integral with and extending across the
90 lower portion of the section 11 after the
manner of a chord but located in spaced re-
lation to the flat face of the section 11.
With reference to Figure 2 it will be seen
that the inner surface of the flange 32 is
95 inclined or beveled so as to form a gradually
narrowing groove or channel for the recep-
tion of the beveled lower edge of the mov-
able section 12. It is thus seen that when
the movable section returns to its normal
100 position with the openings 22 and 23 in
registration the beveled lower edge of the
movable section will be engaged with the
beveled inner side of the flange 30 so that
the opposed flat faces of the sections 11 and
105 12 will be urged into practically gas tight

connection with each other. In this manner the escape of the exhaust gases between the sections 11 and 12 is prevented. Therefore, the flange 30 not only serves as a means to limit the movement of the section 12 in one direction but also as a means to insure a practically gas tight connection between the disk-shaped members 11 and 12.

The movable section 12 is provided with a radial arm 36 having connection with a coiled spring 37 by means of which the openings 22 and 23 are urged into registration. One end of the coiled spring 37 may be anchored to a stationary portion 40 of the vehicle.

The section 12 may be swung on its pivot by a foot pedal connected to a cable 46 and when the cable 46 is operated the section 12 will swing upwardly against the tension of the coiled spring 37. However, when the cable 46 is released the spring 37 will immediately return the section 12 to its normal position and the lower portion of the same will be received in the narrowing groove 50 formed by the flange 30 so that the sections are again in registration and the movement of the products of combustion through the muffler 6 is provided for.

It is to be noted that in returning to the position shown in Figure 2 the lower edge of the disk 12 scrapes away any dust, dirt, grease, oil or the like that may have been deposited on the flat face of the disk 11 and the edge of the disk 11 likewise scrapes the flat face of the disk 12 to maintain the contacting faces clean and smooth.

However, when the sections are not in registration or are in position as illustrated in dotted lines in Figure 3 the products of combustion will exhaust freely out of the exposed end of the exhaust pipe 5. It will be seen that when the cut out is opened the products of combustion do not have to make sharp bends or turns at the cut out and consequently carbon deposits in the cut out are reduced to a minimum and movement of the products of combustion is not in any way obstructed nor retarded.

In order to provide for the escape of the exhaust gases at all times and especially during the swinging movement of the section 12, this section 12 is provided with a series of concentric arcuate openings 40 located in the portion of the section 12 that traverses the opening 22. The openings 40 are of the cross sectional form shown in Figure 4 so that the strength of the section 12 will be preserved while the escape of the gases is facilitated.

The invention forming the subject-matter of this application may be incorporated in

an exhaust pipe at any time without the exercise of unusual skill or without elaborately changing the construction of the vehicle.

In the form of the invention illustrated in Figure 4 the sections 60 and 61 may be provided adjacent the cut-out with bends 66 and 67 so that when the sections are out of registration the products of combustion will be directed downwardly toward the ground so as to reduce the fire hazard to a minimum.

Figure 2 illustrates that the section 9 has one end flared or enlarged as indicated at 73, and received within a socket 75 in one end of the muffler. A suitable strap or clamp 76 may be secured about the socket 75 so as to hold the enlarged or sphere-shaped portion 73 within the socket.

I claim:

1. A cut-out comprising co-acting disk-shaped sections having their opposed sides flatly in contact and provided with openings adapted for registration, means pivotally connecting the disk-shaped sections, one of the sections being provided with a combined stop and guide flange extending in spaced relation across its face and arranged in the path of travel of the other disk-shaped section, spring means urging the openings in the disk-shaped sections into registration, an exhaust conducting member connected to one of the disk-shaped sections and having means whereby the same may be universally connected to a muffler.

2. The combination of an exhaust line divided into two sections, a pair of co-acting disks having their opposed faces flatly in contact and having their outer sides rigidly connected to said sections, one of the sections being stationary and the other being movable, a muffler having universal connection with the movable section of the exhaust line, and means whereby to limit the movement of one of said disks with relation to the other.

3. In a cut-out, a stationary disk and a movable disk pivotally connected to the stationary disk, said disks having central openings adapted for registration, said movable disk having a series of concentric arcuate openings in the portion of the movable disk that traverses the central opening of the stationary disk, said arcuate openings being tapered in cross section.

4. In a cut out, a stationary disk and a movable disk pivotally connected to the stationary disk, said disks having central openings adapted for registration, said movable disk having a series of openings in the portion of the movable disk that traverses the central opening of the stationary disk.

OLIN HENRY WILSON.
